Primary Examiner — Thomas Johannes*Assistant Examiner* — Catherine Posthauer(74) *Attorney, Agent, or Firm* — Thomas J. Horstemeyer, LLP(57) **CLAIM**

The ornamental design for a mirror, as shown and described.

DESCRIPTION

FIG. 1 is a front perspective view of the mirror;
FIG. 2 is a front perspective view of the mirror from a side opposite that of FIG. 1;
FIG. 3 is a front elevational view of the mirror of FIG. 1;
FIG. 4 is a side elevational view of the mirror from the right side of FIG. 1;
FIG. 5 is a side elevational view of the mirror from the left side of FIG. 1;
FIG. 6 is a side elevational view of the mirror from the top side of FIG. 1;
FIG. 7 is a side elevational view of the mirror from the bottom side of FIG. 1; and,
FIG. 8 is a back elevational view of the mirror of FIG. 1.
The broken lines are shown for the purpose of illustrating portions of the mirror and form no part of the claimed design.

1 Claim, 4 Drawing Sheets(56)
